UNITED STATES PATENT OFFICE.

CHARLES EDWARD HAVILAND, OF LIMOGES, FRANCE.

DESIGN FOR A JAR.

SPECIFICATION forming part of Design No. 20,847, dated June 23, 1891.

Application filed May 25, 1891. Serial No. 394,066. Term of patent 14 years.

To all whom it may concern:

Be it known that I, CHARLES EDWARD HAVILAND, a citizen of the United States, residing at the city of Limoges, in the Republic of France, have invented and produced a new and original Design for a Jar and other Articles, of which the following is a specification, reference being had to the accompanying drawings, forming part thereof.

Figure 1 is a perspective view of a jar, showing my design. Fig. 2 is a detached perspective view, partly broken away, of the cover for said jar; and Fig. 3 is a detached detailed top view of the middle portion of said cover.

The leading features of my design in respect to the body of the jar consist of the ornamental scroll F, having an irregular and substantially segmental outline, the conventionalized foliate scroll-sprays G H, harmoniz-

ing with the scroll F, and the irregular fluted 20 edge C around the top of the jar, preferably supplemented by the conventionalized foliate edge scroll D.

The leading features of the design on the concave cover A consist of the ornate irregular edge fluting A' and the ornamental conventionalized scroll-handle B.

What I claim is—

1. The design for a jar or other article, substantially as shown and described.
2. The design for a cover for a jar or other article, substantially as shown and described.

Signed at the city of Limoges, in the Republic of France, this 12th day of May, 1891.

CHARLES EDWARD HAVILAND. [L. S.]
